CALENDAR ATTACHMENT FOR TIMEPIECES AND THE LIKE.

1,402,495.

Specification of Letters Patent.

Patented Jan. 3, 1922.

Application filed October 16, 1920. Serial No. 417,424.

To all whom it may concern:

Be it known that we, THEODORE B. HERTH and EDWIN W. HERTH, both citizens of the United States of America, and residents of 5 Cincinnati, in the county of Hamilton and State of Ohio, have invented a certain new and useful Improvement in Calendar Attachments for Timepieces and the like, of which the following is a specification.

10 This invention relates to a monthly-calendar utility and novelty device adapted to be removably-attached in place on the back of a watch, or on the most convenient portion of other similar apparel of personal 15 use or wear, or to be used "easel-fashion" on a desk or table, or on a mantel or shelf, or at the lower end of a watch fob or chain, as the case or whim may be; and its object is to provide such a device with simple and 20 very convenient means to indicate the month, the numerical day of the month and the name of the day of the week, such means being manually advanced from day to day by the user of the device, but not by driving-connection with the timepiece or other 25 device in connection with which our calendar is used.

The invention consists of a combination of day, week and month display-disks suitably mounted on a central spindle or axis 30 so that they may be actuated independent of each other to make the combined display or indication for each day as the days pass by, and adding to such combination a main- 35 disk or back-plate to which said rotatable disks are connected by the said spindle and which has an opening or sight therein for the actual viewing-display in common of said day, week and month data, and which 40 back-plate has, also, three radially-extending hook-arms and with detachable, as well as adjustable claw or clamp extensions whose outer hook or claw ends are adapted to engage the periphery of the watch-case for 45 detachable, securing-connection therewith.

The details of structure will be fully hereinafter described and then more particularly set forth in the claims that follow.

In the accompanying sheet of drawings— 50 Figure 1 is an enlarged elevation of the back of an ordinary watch or pocket-timepiece showing our improved device in place for use; Fig. 2, a vertical section taken on the dotted line 2, 2, of Fig. 1; Fig. 3, a 55 plan of the display-face of the month indicator-disk; Fig. 4, a plan of the display-

face of the week indicator-disk; Fig. 5, a vertical section taken on the dotted-line 5, 5, of Fig. 4 to show the cross-structure of the said week indicator-disk; Fig. 6, a plan of 60 the display-face of the day indicator-disk; Fig. 7, a plan of the inner recessed or countersunk face of the main-disk and the extended hand-pinion for operating the week indicator-disk; Fig. 8, a miniature perspective showing how the device can be used "easel-fashion" on a desk, table or other place of use and display; and Fig. 9, a front elevation of the device showing it without radial arms and as adapted for use at the 65 lower end of a watch-fob.

7 indicates an ordinary watch or pocket-timepiece having the customary stem-portion 8 and to the back of which our calendar-device is adapted to be detachably-secured by means of three radially-disposed claws or clamp-arms 9, 10 and 11, the latter claw (11) being forked so as to readily straddle or engage the said stem-portion 8 to prevent the said calendar-device shifting 75 or turning around on the said watch.

12 indicates the main-disk which has a series of three, equally-spaced radial arms 13 extending from its periphery.

The arms 13 are bent inwardly at their 85 outer ends to form hooks or stops 14, as best shown in Fig. 2, to successively-engage the series of six parallel, transverse slots 15 provided in the claw-arms 9, 10 and 11 so as to adapt the calendar-device to adjustment in connection with different diameters or sizes of watches. The inner ends of the longitudinally-extensible 90 claws 9, 10 and 11 are outwardly-bent into transversely-slotted short arms or 95 flanges 16 that form guide-ways or guide-eyes whereby the inner ends of the said claws may be moved lengthwise along the radial arms 13 for adjustment to suit 100 different-sized watches.

The main-disk 12 has an arc-shaped opening or sight 17 near that part of its periphery that lies or tends toward the stem-portion 8, and such opening has a lower, shortened, concentric extension 18 that in turn 105 lies or tends toward the center of the watch, as best seen in Fig. 1. This peculiarly constructed opening is intended for a sight through which to view the calendar numbers and other data to indicate the day of the 110 month, the name of the day and that of the month, all closely associated or clustered and

easily read by the carrier or user of the watch, at any time, either on his person or when off of it, as the case may be, or when the device is used "easel-fashion," or as a 5 watch-fob, as shown in several views of the drawings.

We will now proceed to describe the details of the internal structure of our calendar-device, which is made up of three disks, 10 one designated 19 that lies next in turn back of the said main-disk 12; another, designated 20 that lies farther next in turn back of said disk 19; and the last one of the three, designated 21 that lies still farther next in 15 turn back of the said disk 20, all the disks being concentrically mounted on a central spindle or axis 22 that extends through the main-disk 12, which latter does not turn, and thence through the successive rotatable disks 20 19, 20 and 21, suitable washers 23 being inserted on said spindle between the disks 19 and 20 and between the disks 20 and 21, or, in other words, the said washers are placed at either side the orificed or pierced center of the disk 20 to reduce friction between the disks and to facilitate their rotatable-adjustment, without their dragging on each other, when desired to set dates.

The disk 19 is the one that has the names 30 of the twelve months each printed in a given space on its outer face near its periphery, as best shown in Fig. 3, and as more specifically described hereinafter, such names of the months appearing successively in the 35 narrow part 18 of the arc-shaped viewing-sight of the main-disk 12, and suitably-spaced pilot-arms or short projections 23^a extending radially and equidistant apart along the periphery of said month indicator-disk 19, for use as a rotatably propelling or 40 adjusting means for said disk 19 in bringing the desired name of the month into view in said sight or opening 18.

The said month indicator-disk 19 lies directly back of the main-disk 12, but a thin ring or partition-wall 24 is provided that is set or spaced the thickness of the disk 19 away from and concentric with the main-disk 12, and, the said disk 19 being of the 50 same diameter as that of the inner edge of said ring 24, its pilot-arms 23^a extend to the peripheral-edge of said main-disk 12, the edge of the latter being cut away at 25, for a distance coincident with the space that lies between the radial arms 13 at the lower part of the main-disk, as best seen in Fig. 1, to expose or bare one or more of said pilot-arms for convenience in pressing against them with the thumb or a finger in turning 55 the month indicator-disk 19 into the desired month indicating-view in said narrow portion 18 of the sight-opening in the main-disk. The disk 19 is sufficiently free to turn on the spindle in the said space lying between the main-disk and the extended-ring 60

24, but with still enough friction to prevent the disk 19 turning accidentally on the spindle away from its set-date indicator-position.

The said ring is spaced from the main-disk 12 by means of a strip of metal 26 that 70 is the shape of and lies between a semicircular extension 27 of the main-disk, adjacent the date viewing-sight 17, 18, and a similar or corresponding, parallel extension 28 of the said ring. 75

A hand-pinion or small spur-wheel 29 is mounted on a transverse pin or short bolt 30 centrally set in the said registering semi-circular extensions 27 and 28 and their intervening metal strip 26. Said hand pinion 29 is provided for convenient engagement with the toothed inset edge 30^a of the week-day indicator-disk 20, such toothed edge 30^a being best seen in Figs. 4 and 5 and provided for the propulsion of the disk 20 on the 80 central axis 22 by means of said spur-wheel 29 to set up the desired day of the week that appears on the respective radial arms 31, in due turn in the broad part of the sight 17 of the main-disk 12, the viewing-face of said disk 20 being best seen in Fig. 4, detached from the rest of the device. 85

The hindmost disk 21 has a serrated edge 32 whereby it is propelled or rotated on the said axis 22 by thumb or finger pressure, to bring up the successive days of the month into view immediately to the right of the week-days in the sight 17, so as to complete the indication each day as the days progress. 90

Ordinarily, with a watch that is carried on the person, and which is wound every day at a set time, say at the time of rising in the morning, the calendar part of the attachment is set for that day at once and the user can readily see the date as well as the 100 time of day whenever he views his timepiece during the day, or during the evening before retiring. Thus accuracy can be depended on from day to day and the device herein will make a very useful and attractive appendage. 110

The week-day disk 20 has an extra thickness 33 beyond the toothed inset edge 30^a, as best seen in Fig. 5, such thickness corresponding to that of the ring 24, and the 115 front face of said extra thickness 33 lies adjacent to but not touching the back of the month indicator-disk 19, so as to aline the said toothed edge 30^a with that of the spur-wheel 29 and thus makes the device just that 120 much more compact and reduces the thickness of the entire device to a minimum for convenience and comfort in wearing it on the watch in one's pocket. 125

In the preparation of the face of the month indicator-disk 19 we divide up each space that lies between the pairs of radial pilot-arms 23^a into four equal parts, the two central ones being utilized for two succeeding months' names and the two end ones 130

being left blank, as best seen in Fig. 3. The prime object of this feature is to be able to make an indication of one of the months in the narrow part 18 of the viewing-sight of the main-disk 12 without any of the said pilot-arms 23^a obstructing the view from either the days of the week or of the month in the main part 17 of said viewing-sight that would otherwise occur.

10 In the "easel" form of device seen in Fig. 8 we omit the extension-claw arms 9 and 10 of Fig. 1, and utilize the two lower radial arms 13 of the main-disk 12 for foot-rests and the upper radial arm 13 with its 15 extension 11 as a back-stop or prop, the said arm 13 being bent at a suitable inclination rearwardly and adapted to be adjusted longitudinally to suit the degree of inclination desired. This use of the device is very 20 attractive as an ornament of utility on the desk, table, shelf or mantel, as desired.

In the "fob" form of device seen in Fig. 9 we omit the claw and radial arms from the main-disk 12 and suitably secure the 25 remainder thereof on the face of the fore pendent part 34 of the ordinary watch-fob. This feature is both useful and ornamental and illustrates the adaptability of the device to many uses besides that of in connection 30 with a watch or similar pocket timepiece.

We claim:—

1. A calendar-attachment for watches and the like comprising a main-disk having a combined date-viewing sight-opening there- 35 in, radial arms extending from the periphery of said main-disk, longitudinally-extensible clamping claw-arms mounted at the outer ends of the said radial arms, a central spindle or axis, an independent month-indi- 40 cator rotary-disk mounted on said spindle back of said main-disk and having short radial pilot-arms extending from its periphery, an independent week-day indicator-disk mounted on said spindle back of said month 45 indicator-disk and having spaced radial

arms on which the respective names of the days are displayed, a toothed edge along the periphery of the said week-day disk, a spur-wheel provided on a lateral extension of the main-disk and adapted to operatively 50 engage the said inset toothed edge on the week-day disk, and an independent day indicator-disk mounted on the said spindle back of said week-day indicator-disk and having a notched or serrated edge to facilitate its rotation in bringing up the desired numeral to indicate that of the day of the month to appear for reading in the broad part of the viewing-sight alongside the name of the day and above the name of the month. 55

2. A calendar-attachment for watches and the like comprising a main-disk having radial arms whose inner ends are bent or flanged inwardly, extension-arms having claw or hook-shape outer ends adapted to engage the rim or edge of the watch, a series of transverse slots in each of said extension-arms adapted for adjustable-engagement by the said inwardly-disposed flanges of the said radial arms, a central spindle or axis 70 projecting from said main-disk inwardly toward the watch, an open viewing-sight in the main-disk, a spur-wheel mounted to turn on a lateral extension of said main-disk, a series of independent month, week and day 75 indicator-disks rotatably mounted on said spindle in rotation back of the main disk and one of said disks being provided with inset teeth along its main periphery to adapt it to engagement by the said spur-wheel for 80 hand-rotation in indicating the week-days, spacing-washers at both sides of said week-disk, and a spacing-ring on the back of the main disk adapted to house or accommodate a part of the thickness of the said disk that 85 has the said inset peripheral teeth, substantially as set forth.

THEODORE B. HERTH.
EDWIN WM. HERTH.
